UNITED STATES PATENT OFFICE.

LOUIS A. GILSON, OF LUDLOW, KENTUCKY.

HARNESS.

1,146,562.

Specification of Letters Patent. Patented July 13, 1915.

Application filed March 25, 1914. Serial No. 827,058.

To all whom it may concern:

Be it known that I, LOUIS A. GILSON, a citizen of the United States, and a resident of Ludlow, in the county of Kenton and State of Kentucky, have invented certain new and useful Improvements in Harness, of which the following is a specification.

My invention relates to harness, and more especially to harness for light driving and racing purposes, and its object is to simplify the construction of such harness, render it more efficient and dependable, and enable the application and adjustment of the harness to the horse to be made more quickly.

My invention consists in the parts and in the details of construction and arrangement of parts as will hereinafter be more fully described and claimed.

In the drawings: Figure 1 is a general perspective view of a harness embodying my invention, the horse, and parts of the harness not involved in my invention, being shown by dotted lines; Fig. 2 is a partial view similar to Fig. 1, showing a modification of my invention; Fig. 3 is an enlarged perspective view of the saddle and girth disconnected from the other parts of the harness, and with the straps represented as unfastened and drawn out from the saddle and girth to more clearly illustrate the details of construction of these parts; Fig. 4 is a detail perspective view of a combination shaft tug and support; Fig. 5 is a detail perspective view of one of the bars with the D-clips at its opposite ends; Fig. 6 is a vertical cross section through the saddle and its associated parts, looking to the rear; Fig. 7 is a vertical section corresponding to that of Fig. 6, but enlarged and showing the means for adjusting the shaft tug; and Fig. 8 is a detail of the shaft-tug fastening means.

In my invention, the general arrangement of the parts of the harness connected to the saddle is improved, and the construction of the saddle is adapted to this arrangement, as well as having improved means for attachment to the shaft.

As I prefer to construct my invention, and as shown in the drawings, the saddle 1 comprises the skirt 2 made up of an inner thickness 3 and an outer thickness 4 surmounted by the jockey 5, which extends down about the usual distance on each side.

As here shown, the saddle is reinforced by a resilient metal tree 6, lying under the

inner thickness 3 and extending down at each side considerably farther than does the jockey 5; and a pad 7, with suitable filling 8 and of suitable form, is provided on the inside of the saddle with the tree 6 contained therein.

It will be understood that my improved saddle may be full padded, but, as here shown, it is provided with pad bottoms 9 from the ends of the pad 7 at each side down to the lower ends of the skirt 2, which skirt tapers somewhat toward said lower ends. Also, in any case, the tree 6 may be omitted if desired.

The upper safety strap 10 lies over the jockey 5, and at the top, in the middle, a tee-hook 11 has a shank 12 passing down through the safety strap 10, the jockey 5, the two layers 3 and 4 of the saddle skirt and through the metal tree 6 with a nut 13 which binds them all together. This safety strap 10 is also preferably stitched to the jockey 5 down to a point near the lower end of the jockey on each side, where terrets 14 have shanks 15 passing down through the safety strap 10 and through the jockey 5 with a flat spring 16 received between the safety strap 10 and the jockey 5 with this shank 15 passing through it, and with a socket plate 17 placed on the lower side of the jockey, through which the shank 15 also passes and is riveted down thereagainst, so that in this part of the harness the safety strap 10, flat spring 16, jockey 5 and socket plate 17 are held firmly together by the terret. The middle part of the outer thickness 4 of the skirt 2 is cut away, and the socket plate 17 extends down from the terret along the skirt and has channel legs 18 which fit in the cut-away part of the thickness 4, so that the space between the legs 18 forms a socket. This cutting away of the thickness 4 is continued up close to the terret at the top, so that the socket formed is continuous from the lower end of the jockey up to this point. The inner thickness 3 is slotted to receive the lower edges of the legs 18, and this inner thickness 3 thus forms the bottom or inner side of the socket for its entire length, supported laterally by the legs 18 in the slots, and is supported outward by the tree 6; or if the tree 6 were omitted would be supported outward by the pad 7 and its filling 8 alone.

The combined shaft tug and support 19

110

has an upper or strap extension 20 which is received in the above described socket, and may be extended therein to the full depth up near the terret 11. The lower end of this 5 tug 19 is in the form of a loop 21 through which the shaft 22 is extended. The strap extension 20 of the tug 19 has a series of perforations 23, and the flat spring 16 extends down past the lower end of the socket plate 10 and jockey and has a plunger 24 which extends down through a bushing 25 that is fitted in an opening in the socket plate and 15 an opening in the jockey, with a flange 26 fitting down on the upper surface of the jockey around the opening, this flange being riveted through the jockey to the socket plate. This plunger 24 is normally pressed down by the flat spring 16 on which it is carried, and will enter any one of the perforations 23 in the strap extension 20 of the 20 tug 19. By this means the tug 19 may be quickly adjusted up or down to give the shafts any desired position. Preferably, the 25 inner thickness 3 and the tree 6 are also perforated, and the plunger 24 is made long enough to extend through these parts when in normal position, and thus be reinforced by the metal tree 6. This arrangement allows the shaft tug to be quickly adjusted 30 and causes it to be held firmly in any adjusted position. This shaft tug is also less bulky, and has no loose extended parts to form obstacles and resist the pressure of the air when the horse is traveling at high speed, 35 as well as to make a noise, which is disconcerting both to the horse and to the driver. Also, this tug supported and adjusted in this manner is especially adapted to have its loop 21 made of round cross section as shown 40 instead of being in the form of a flat strap to pass around the shaft. Such a loop may be made with the seam outside away from contact with the shaft and never exposed to wear on the shaft, so that the tug is far 45 more durable than one with a somewhat flat strap in which the seam or seams must receive part of the wear and which, when worn, allow the tug to come apart.

The safety strap 10, passing down over 50 the flat spring 16 and wound around the shaft 22, reinforces the spring 16 and holds it positively in its normal position with this plunger 24 through the perforation of the strap extension 20 of the tug 19, and this 55 strap also reinforces the tug 10 at the shaft forming a firm attachment to the shaft.

The inside or pocket girth 27 has the 60 pockets 28 on its upwardly extended ends, and these receive the tapered lower ends of 65 the saddle skirt 2, this girth 27 being continuous under the body of the horse and having a middle pocket 29 through which an outside girth 30 passes, having a buckle 31 at each end, and said buckle receiving the 65 lower end of the safety strap 10 after said

safety strap has been wound around the shaft 22. This outside girth 30 is made long enough so that the buckle 31 will be well up at the sides of the horse's body and not to be liable to produce chafing in the region of 70 the horse's front legs. To attach the inner or pocket girth 27 to the saddle, the saddle is provided with clips 32 at the sides, which are preferably provided with metal reinforcements 33 inside, with links 34 swinging 75 in them, through which links straps 35 pass down to the girth 27 somewhat below the pockets 28, being folded and stitched thereto, so that outer members 36 of this strap 35 meet and are secured together by a buckle 80 37 at each side of the harness. A lower safety strap 38 passes through the lower pocket 29 along with the outer girth 30 and is brought up on each side, inside the shaft 22, wrapped therearound, and then brought 85 down and held by a buckle 39 on the standing part of this strap 38.

Shortly below the end of the jockey, at each side of the harness, the saddle skirt has a forward upper D-clip 40 and a similar 90 rear upper clip 41 and farther down has a forward lower D-clip 42 and a similar rear lower clip 43, the forward and rear clip in each instance being integral on a bar 44 or 45 respectively, which is inclosed between 95 the thicknesses 3 and 4 of the skirt 2 with rivets passing through the thickness 6 and through the bars. The lower clips with their bar 45 are close to the link 34, and a rivet passes through the reinforcement 33 of 100 the clip 32 of the link 34 and through the bar 45. The forward end of the shaft 22 has the thimble 46 fitting over it, and the thimble strap 47 is attached to the thimble 46 at the inner side of the shaft and extends 105 back through the upper forward clip 40 and then forward through a buckle 48 attached to its own standing part. The breast strap 49 passes around the horse's breast from the lower forward clip 42 on one side to the corresponding clip on the other side, passing 110 through the clips and being secured by buckles 50 on the standing parts of the strap at each side of the harness. The trace 51 extends through the lower rear clip 43 and 115 is secured by a buckle 52 on its own standing part, this trace extending back for suitable attachment to the vehicle. Another trace 53 is stitched to the trace 51 some distance back from the saddle, and extends forwardly 120 and upwardly through the upper rear clip 41, then passing back through a buckle 54 on its own standing part. The T-hook 11 has the neck strap 55 passing behind it and 125 forwardly and downwardly through a loop 56 at the extreme forward part of the breast strap 49; and the over check 57 is also fastened to the T-hook. Directly to the rear of the T-hook 11, on the rear edge of the extreme upper part of the saddle skirt, is a D- 130

clip 58, which is fixed between the thicknesses 3 and 4 of the skirt 2 and forms the means for connecting the crupper 59 to the saddle.

5 My improved harness is well adapted for use without the breast strap 49, and, consequently, without the neck strap 55, as shown in Fig. 2. Where the breast strap is dispensed with, as here shown, I prefer to 10 provide the thimble 46 with an additional lower thimble strap 60 which passes back and down and connects through the forward lower D-clip 42 which had received the breast strap 49, being secured by means of a 15 buckle 61 in a manner similar to that of securing the upper thimble strap 47 by the buckle 48.

The other parts of the harness not herein specifically mentioned, and which are merely 20 indicated by dotted lines, are of well known construction and arrangement, requiring no special description herein.

In my improved harness, constructed as shown in Fig. 1, the trace 51 is brought in 25 direct line with the breast strap 49, eliminating useless vertical strains upon the saddle as well as upon the horse's body; and making the trace and breast strap more efficient in their functions as tension members.

30 The additional trace 53 braces the main trace 51, as well as the saddle; and the thimble strap 47, acting as a hold back strap, will usually be stretched in substantially a horizontal direction; and, having its attach-

35 ment directly forward from the attachment of the additional trace or brace 53, the same advantage is derived in the operation of these parts as was above noted with respect to the operation of the main trace 51 and

40 brace strap 53. The neck strap 55 supports the forward part of the breast strap 49 in a most efficient manner; and with these parts as well as the girths and safety straps properly adjusted, a very firm hitching arrangement is

45 afforded, with a minimum of discomfort to the horse but with a high degree of safety and reliability, and one which is very quickly adjusted to the horse each time the hitching is to be done. The lower thimble strap, in

50 the modification shown in Fig. 2, supports the saddle forwardly at the point where the breast strap serves this purpose in the example shown in Fig. 1, affording a very firm hitching arrangement by pulling backward

55 on the end of the shaft, and against the firm attachment of the tug 19 and its safety straps 10 and 38, so that all lost motion is practically eliminated, and with the saddle firmly fixed around the horse's body by means of

60 the improved girths and safety strap, a thoroughly safe and efficient hitching arrangement is provided for light driving, especially for racing purposes.

The adjustment of the shaft tug in the 65 saddle by the means hereinbefore described

especially contributes to the ease of adjusting the harness during the hitching; and the provision of the two safety straps 10 and 38 to reinforce the tug, as well as reinforce the tug adjusting and fastening means, especially contributes to the safety and reliability of the harness.

Having fully described my invention, what I claim as new and desire to secure by Letters Patent is:

1. In harness, the combination of a saddle, a shaft tug to receive the shaft and comprising a strap extension, said saddle comprising a jockey and having a socket extending lengthwise under the jockey and said strap extension lying within this socket, and engaging means therein for holding the tug for adjustment up and down with respect to the saddle, said engaging means in the socket having a movable part outside the jockey for manipulating the engaging means, and a safety strap lying over the jockey and drawn down over the movable part of the engaging means, thereby reinforcing it in its holding of the tug, said safety strap being adapted to be wrapped around the shaft adjacent to the tug and to pass down along the saddle, a pocket girth comprising pockets receiving parts of the saddle, and comprising another pocket 95 adapted to lie directly under the animal's body, an outer girth passing through this pocket, and means for adjustably securing said safety strap to this outer girth.

2. In harness, the combination of a saddle, a shaft tug to receive the shaft and comprising a strap extension, said saddle comprising a jockey and having a socket extending lengthwise under the jockey, and said strap extension lying within this socket, and engaging means therein for holding the tug for adjustment up and down with respect to the saddle, said engaging means in the socket having a movable part outside the jockey for manipulating the engaging means, and a safety strap lying over the jockey and drawn down over the movable part of the engaging means thereby reinforcing it in its holding of the tug, said safety strap being adapted to be wrapped around the shaft adjacent to the tug and to pass down along the saddle, a pocket girth comprising pockets receiving parts of the saddle and comprising another pocket adapted to lie directly under the animal's body, an outer girth passing through this pocket, means for adjustably securing said safety strap to this outer girth, and a second safety strap passing through this pocket along 110 with the outer girth and adapted to be secured around the shaft at each side of the animal.

3. In harness, the combination of a saddle comprising skirts, a shaft tug to receive the shaft and comprising a strap extension, said

- saddle comprising a jockey and having a socket extending lengthwise under the jockey, said strap extension lying within this socket, and engaging means therein for holding the strap extension for adjustment up and down with respect to the saddle, said engaging means in the socket having a movable part outside the jockey for manipulating the engaging means, and a safety strap 10 lying over the jockey and drawn down over the movable part of the engaging means thereby reinforcing it in its holding of the tug, said safety strap being adapted to be wrapped around the shaft adjacent to the tug and to pass down along the saddle, a pocket girth comprising pockets receiving the saddle skirts, and means for adjustably connecting the saddle skirts to the pocket girth with said skirts held in the pockets.
- 15 4. In harness, the combination of a saddle comprising skirts, a shaft tug to receive the shaft and comprising a strap extension, said saddle comprising a jockey and having a socket extending lengthwise under the jockey, said strap extension lying within said socket, and engaging means on the strap extension for holding the tug for adjustment up and down with respect to the saddle, said engaging means in the socket 20 having a movable part outside the jockey for manipulating the engaging means, and a safety strap lying over the jockey and drawn down over the movable part of the engaging means, thereby reinforcing it in its holding of the tug, said safety strap being adapted to be wrapped around the shaft adjacent to the tug and to pass down along the saddle, a pocket girth comprising pockets to receive the skirts of the saddle, a link 25 30 35 40 45 50 55 60 65 70 75 80 85 90 95 100 105 110 115 120 125 130 135 140 145 150 155 160 165 170 175 180 185 190 195 200 205 210 215 220 225 means for holding said extension for adjustment up or down in the socket, to adjust the tug up or down on the saddle.

8. In harness, a saddle comprising a skirt with a socket extending lengthwise therein, and a shaft tug comprising a strap extension lying within the socket, said extension having a series of perforations therealong, and a yieldably mounted plunger extending into the socket to enter any one of the perforations and hold the extension for adjustment along the socket, to adjust said tug up or down on the saddle.

9. In harness, a saddle comprising a skirt with a socket extending lengthwise therein, and a shaft tug comprising a strap extension lying within the socket, a socket plate lying within the socket, a flat spring fixed to the socket plate, and a plunger on the flat spring, extending through the socket plate, said strap extension having a series of perforations therealong, into any one of which the plunger may extend to hold the strap extension in the socket, for adjustment of said tug up or down on the saddle.

10. In harness, a saddle comprising a skirt and a jockey surmounting the skirt, said skirt having a socket under the jockey, a tug comprising a strap extension lying within the socket, and yieldable means mounted upon and extending through the jockey and holding said extension in the socket for adjustment of the extension along the socket, to adjust the tug up or down in the saddle, and a safety strap overlying the jockey and engaging with the means that holds the tug extension to reinforce said means.

11. In harness, a saddle comprising a skirt and a jockey surmounting the skirt, said skirt having a socket under the jockey, a tug comprising a strap extension lying within the socket, means holding said extension in the socket for adjustment of the extension along the socket, to adjust the tug up or down in the saddle, and a safety strap overlying the jockey and engaging with the means that holds the tug extension to reinforce said means.

12. In harness, a saddle comprising a skirt and a jockey surmounting the skirt, said skirt having a socket under the jockey, a tug comprising a strap extension lying within the socket, means holding said extension in the socket for adjustment of the extension along the socket, to adjust the tug up or down in the saddle, and a safety strap overlying the jockey and engaging with the means that holds the tug extension to reinforce said means, said tug receiving and holding a shaft and said safety strap being wrapped around the shaft adjacent to the tug and reinforcing the tug in holding the shaft.

13. In harness, a saddle comprising a skirt with a socket extending lengthwise therein, and a shaft tug comprising a strap extension lying within the socket, and yieldable

extension lying within the socket, said extension having a series of perforations therealong, and a yieldably mounted plunger extending into the socket to enter any one of 5 the perforations and hold the extension for adjustment along the socket, to adjust said tug up or down on the saddle, said plunger also extending through said skirt from the socket, and said tree having a perforation 10 through which the plunger also extends, whereby the plunger is reinforced by the tree.

14. In harness, a saddle comprising a skirt made up of two thicknesses of material and a jockey overlying the outer thickness for part of its extent, said outer thickness having a part cut away under the jockey, forming a socket extending lengthwise within the skirt, and the inner thickness 20 of material of the skirt forming the bottom or inner side of the socket, a socket plate lying under the jockey and comprising channel legs extending along the sides of the socket formed in the outer thickness of material, and the inner thickness of material having slots into which the channel legs extend, whereby said legs form the sides of the socket at its entrance and whereby they reinforce the thicknesses of material 25 of the saddle skirt laterally, a plunger yieldably mounted and extending through the socket plate into the socket, and a tug comprising a strap extension lying in the socket, said extension having perforations which 30 35 the plunger enters, whereby the tug is held for adjustment up and down with respect to the saddle skirt.

15. In harness, a saddle comprising a skirt made up of two thicknesses of material and a jockey overlying the outer thickness for part of its extent, said outer thickness having a part cut away under the jockey, forming a socket extending lengthwise within the skirt, and the inner thickness of material of 40 the skirt forming the bottom or inner side of the socket, a socket plate lying under the jockey and comprising channel legs extending along the sides of the socket formed in the outer thickness of material, and the inner thickness of material having slots into which the channel legs extend, whereby said legs form the sides of the socket at its entrance and whereby they reinforce the thicknesses of material of the saddle skirt laterally, and a safety strap secured over the jockey and over the yieldable mounting of the plunger to hold the plunger in a perforation of said strap extension of the tug.

16. In harness, a saddle comprising a skirt made up of two thicknesses of material and a jockey overlying the outer thickness for part of its extent, said outer thickness having a part cut away under the jockey, forming a socket extending lengthwise within 50 the skirt, and the inner thickness of material

of the skirt forming the bottom or inner side of the socket, a socket plate lying under the jockey and comprising channel legs extending along the sides of the socket formed in the outer thickness of material, and the inner thickness of material having slots into which the channel legs extend, whereby said legs form the sides of the socket at its entrance and whereby they reinforce the thicknesses of material of the saddle skirt laterally, a flat spring outside the jockey, and means extending through the jockey and securing the spring to the socket plate, a plunger mounted on the flat spring and extending through the jockey and socket plate, 70 and a tug comprising a strap extension with perforations lying within the socket, said plunger entering the perforations whereby the tug is held for adjustment up and down with respect to the saddle skirt. 75

17. In harness, a saddle comprising a skirt made up of two thicknesses of material and a jockey overlying the outer thickness for part of its extent, said outer thickness having a part cut away under the jockey, forming a socket extending lengthwise within the skirt, and the inner thickness of material of the skirt forming the bottom or inner side of the socket, a socket plate lying under the jockey and comprising channel legs extending along the sides of the socket formed in the outer thickness of material, and the inner thickness of material having slots into which the channel legs extend, whereby said legs form the sides of the socket at its entrance and whereby they reinforce the thicknesses of material of the saddle skirt laterally, a flat spring outside the jockey, and means extending through the jockey and securing the spring to the socket plate, a plunger mounted on the flat spring and extending through the jockey and socket plate, a tug comprising a strap extension with perforations lying within the socket, said plunger entering the perforations whereby the tug is adjusted with respect to the saddle skirt, and a bushing extending through the jockey to the socket plate, around the plunger, and comprising a flange lying over the outside of the jockey, and means fastening the flange to the socket plate through the jockey and holding the bushing and the jockey down upon the socket plate. 90 95 100 105 110 115

18. In harness, a saddle comprising a skirt made up of two thicknesses of material, and a jockey overlying the outer thickness for part of its extent, said outer thickness having a part cut away under the jockey, forming a socket extending lengthwise within the skirt, and the inner thickness of material of the skirt forming the bottom or inner side of the socket, a socket plate lying under the jockey and comprising channel legs extending along the sides of the socket formed in the outer thickness of material, and the 120 125 130

- inner thickness of material having slots into which the channel legs extend, whereby said legs form the sides of the socket at its entrance and whereby they reinforce the thicknesses of material of the saddle skirt laterally, a flat spring lying outside the jockey, a terret having a shank passing through the flat spring, through the jockey and through the socket plate and fixed therein, thereby holding the flat spring, the jockey and the socket plate tightly together, a plunger carried on said flat spring and extending through the jockey and through the socket plate, and a tug comprising a strap extension with perforations, lying within the socket, said perforations receiving the plunger, whereby the tug is held for adjustment up and down with respect to the saddle skirt.
19. In harness, a saddle comprising a skirt made up of two thicknesses of material and a jockey overlying the outer thickness for part of its extent, said outer thickness having a part cut away under the jockey, forming a socket extending lengthwise within the skirt, and the inner thickness of material of the skirt forming the bottom or inner side of the socket, a socket plate lying under the jockey and comprising channel legs extending along the sides of the socket formed in the outer thickness of material, and the inner thickness of material having slots into which the channel legs extend, whereby said legs form the sides of the socket at its entrance, and whereby they reinforce the thicknesses of material of the saddle skirt laterally, a plunger yieldably mounted and extending into the socket, and a tug comprising a strap extension with perforations, lying within the socket and receiving the plunger, whereby the tug is held for adjustment up and down with respect to the saddle skirt, and a resilient tree lying within the saddle skirt and reinforcing said skirt, the inner thickness of material of the skirt and said tree having perforations through which said plunger extends, whereby the plunger is reinforced by engagement through the tree.
20. In harness, a saddle comprising a skirt made up of two thicknesses of material and a jockey overlying the outer thickness for part of its extent, said outer thickness hav-
- ing a part cut away under the jockey, forming a socket extending lengthwise within the skirt, and the inner thickness of material of the skirt forming the bottom or inner side of the socket, a socket plate lying under the jockey and comprising channel legs extending along the sides of the socket formed in the outer thickness of material, and the inner thickness of material having slots into which the channel legs extend, whereby said legs form the sides of the socket at its entrance and whereby they reinforce the thicknesses of material of the saddle skirt laterally, a tug comprising a strap extension lying within the socket, means for adjustably securing the strap extension in the socket, and interior padding means comprised in the structure of said saddle, supporting the inner thickness of material of the skirt where it forms the inner side or bottom of the socket.
21. In harness, a saddle comprising a skirt made up of two thicknesses of material and a jockey overlying the outer thickness for part of its extent, said outer thickness having a part cut away under the jockey, forming a socket extending lengthwise within the skirt, and the inner thickness of material of the skirt forming the bottom or inner side of the socket, a socket plate lying under the jockey and comprising channel legs extending along the sides of the socket formed in the outer thickness of material, and the inner thickness of material having slots into which the channel legs extend, whereby said legs form the sides of the socket at its entrance and whereby they reinforce the thicknesses of material of the saddle skirt laterally, a tug comprising a strap extension lying within the socket, means for adjustably securing the strap extension in the socket, a resilient tree for the saddle lying against the inner side of the inner thickness of material of the skirt and reinforcing said inner thickness where it forms the inner side or bottom of the socket, and padding means around said tree inside the saddle skirt.

LOUIS A. GILSON.
